UNITED STATES PATENT OFFICE.

HENRY COURTEEN, OF SUNBURY-ON-THAMES, ENGLAND.

OIL LAMP.

Application filed May 13, 1921. Serial No. 469,316.

(GRANTED UNDER THE PROVISIONS OF THE ACT OF MARCH 3, 1921, 41 STAT. L., 1813.)

To all whom it may concern:

Be it known that I, HENRY COURTEEN, a subject of the King of Great Britain and Ireland, residing at 5 River Terrace, Sunbury-on-Thames, Middlesex, England, have invented certain new and useful Improvements in Oil Lamps (for which I have filed an application in England Feb. 6, 1920, Patent No. 164,423), of which the following is

10 a specification.

This invention relates to lamps used in imitation of candles, that is to say of lamps comprising a cylindrical casing of a size corresponding to that of a candle in which 15 a liquid illuminant is burnt.

According to the invention an oil lamp is provided comprising a casing or reservoir filled with absorbent material which is open at its lower end and is adapted at its lower 20 end to be fitted into a socket in the manner hereinafter described.

The invention comprises the combination of a casing or reservoir filled with absorbent material and open at or near its lower 25 end, and a socket provided with a base and adapted for the reception at its lower end of the said casing or reservoir and to form an annular space to surround the lower end of the said casing or reservoir and into 30 which the liquid illuminant may be poured.

The invention comprises the constructional features hereinafter described.

The socket of the holder may in the main part be formed as a truncated cone in 35 which the larger end of the cone is uppermost and the smaller end is secured to the base of the holder and the upper end of the conical part of the socket is flared or extends outwardly for the reception of any 40 liquid that may rise upwardly on the casing being passed into the socket.

The casing or reservoir is advantageously provided of cylindrical form and may at 45 its lower end be formed of a conical shape to engage within the socket at its lower end. The outwardly flaring part of the socket may be formed with an inwardly protruding flange for assistance in the support of the casing or reservoir when introduced into 50 the socket.

It will be understood that the construction immediately before described may be modified in many details without departing from the essential features of the invention which

involve the use of a socket for the candlestick of such a shape and capacity as to receive the charge of liquid illuminant and to permit of the casing or reservoir being introduced into the socket in such manner that while the liquid illuminant has access 60 to within the lamp casing the latter is held substantially in an upright position in the socket.

The cap provided at the upper end of the lamp casing may be applied in position 65 with a loose fit or it may be screwed into position or otherwise applied and it may be centrally provided with a tube through which a wick may pass, and the tube may be provided with holes or slots by means of 70 which the wick may be adjusted or any other means may be provided upon the cap for adjusting the wick. It will furthermore be understood that the casing of the lamp may be filled with wick alone but it is 75 preferred to provide cotton wool, wadding, asbestos fibre or the like for the absorption of the charge of liquid illuminant, and to avoid the possibility of spilling of the liquid in the case of the holder being upset.

The invention is illustrated by way of example in the accompanying drawing in which—

Figure 1 represents an elevation partly in section of a candle lamp provided according 85 to the invention.

Figure 2 is a sectional plan on the line 2—2 of Figure 1,

Figure 3 is a plan view of the shade or reflector.

Figure 4 is a detail view of the lower part 90 of the lamp casing or reservoir.

As illustrated in the accompanying drawing the casing or reservoir *a* is provided of a tubular form to take the place of a candle, and is open at its lower end and its lower end may be formed of a conical or other shape to fit or engage within the lower end of the socket or holder *b*. The socket *b* is advantageously of a conical form such 100 as represented in Figure 1 and at its upper part is provided with an integral plate *c* of a dish-shape having a central hole therein, the internal edge of the plate being advantageously provided of such a form as 105 indicated in Figure 2, that is to say by forming it with alternate projections *c*¹ and recesses *c*² of similar shape, so that while the

plate *c* serves for the support of the casing or reservoir *a* the dish shaped part *c* is adapted for pouring the liquid illuminant into the annular space or cavity *b*¹ between the socket *b* and the casing or reservoir *a*. The socket *b* is thus open. The plate *c* may be rendered integral with the socket *b* for example by soldering the edges or surfaces in contact.

10 As before described the casing or reservoir *a* serves to contain an absorbent material such as cotton wool and its lower end is advantageously provided of an irregular form to permit of the liquid illuminant passing into the casing or reservoir so as to be absorbed by the absorbent material. This may be done by forming V-shaped notches *a*¹ at the edge of the casing *a* as illustrated in Figures 1 and 4. At the upper end the 15 casing or reservoir *a* is provided with a wick tube *d*, and this wick tube is advantageously provided with a spiral ledge or thread *e* to engage with the spiral lower edge *f*¹ of the centrally disposed boss *f* which serves to carry the conical reflector *g*. The boss *f* is integrally provided with diametrically disposed arms *f*², whose opposite ends are integrally secured by brazing, soldering or otherwise to the wall of the shade 20 or reflector *g*.

The shade or reflector *g* is advantageously provided of the form of a hollow truncated cone as illustrated in Figure 1 which may be cut in a plane parallel with the axis of the cone to form a lateral aperture *g*¹ through which the light may be outwardly reflected.

It will be understood that the shade or reflector *g* may be capable of rotation upon the wick tube *d* and in its rotation is raised or lowered so that its upper edge thus serves to reduce or to increase the amount of flame.

An absorbent material such as cotton wool or the like may be inserted in the annular space *b*¹ in the socket, and in such a case a cylindrical perforated tube may be provided to form an internal wall *h* (Figure 1) for the annular space *b*¹, through which the casing or reservoir *a* passes. Furthermore 45 a cover plate *i* (Figure 1) may be loosely mounted in position over the dish-shaped plate *c*.

The shade or reflector may be dispensed with.

50 I claim:

1. A lamp comprising in combination a cylindrical casing in the form of a candle, open at its lower end and closed at its upper end, a burner tube mounted at the upper end of the said casing, a wick within the said burner tube, absorbent material filling the said casing by which the casing is adapted to serve as a reservoir for the liquid illuminant, and a socket adapted for the removable mounting therein of the lower end of

the said casing, said socket being adapted to form an annular space surrounding the lower inserted end of the said casing whereby the annular space serves as a filling receptacle for the liquid illuminant on the said casing being inserted within the said socket, substantially as described. 70

2. A lamp comprising in combination a cylindrical casing in the form of a candle, open at its lower end and filled with absorbent material, a burner wick tube at its opposite closed end and a socket for said casing having a supporting base, said socket being adapted for the firm but removable mounting therein of the lower end of the 75 said casing, said socket being open at its upper end and being capable of closure by a loose cover plate, substantially as described. 80

3. A lamp comprising in combination a cylindrical casing in the form of a candle, open at its lower end and closed at its upper end, a burner wick tube mounted at its upper end, a wick within said tube, an absorbent material filling the said casing by 85 which the casing is adapted to serve as a reservoir for the liquid illuminant, and a socket adapted for the reception and removable retention of the lower end of the said casing, said socket having an inwardly protruding 90 flange near its upper end formed with openings through which the liquid illuminant may pass into the annular space between the socket and the lower end of the casing, substantially as described. 95

4. A lamp comprising in combination a cylindrical casing in the form of a candle, open at its lower end and closed at its upper end, a burner wick tube mounted at its upper end, a wick within the said tube, absorbent material filling the said casing, a reflector, adapted for reflection and for protection of the flame, mounted at the upper end of the 100 said casing, and a socket adapted for the reception and removable retention of the 105 lower end of the said casing, substantially as described. 110

5. A lamp comprising in combination a cylindrical casing in the form of a candle, absorbent material filling the said casing, a 115 burner wick tube at one end of the said casing, a reflector adapted for the purpose of reflection and protection of the flame, said reflector comprising a centrally disposed boss, said boss being adapted to be applied upon the upwardly protruding part of the wick tube, and means by which the centrally disposed boss is raised or lowered on rotation on the reflector, and a socket for the reception and removable retention of the 120 said casing, substantially as described. 125

6. A lamp comprising in combination a cylindrical casing filled with absorbent material closed at its upper end, a burner wick tube mounted at its upper end, a wick within 130

the said tube, a socket adapted for the reception and removable retention of the lower end of the said casing, said socket forming with the said lower end of the casing an annular space, and absorbent material within the said annular space, substantially as described.

7. A lamp comprising in combination a cylindrical casing filled with absorbent material closed at its upper end, a burner wick tube mounted at its upper end, a wick

within the said tube, a socket adapted for the reception and removable retention of the lower end of the said casing, said socket forming with the said lower end of the casing an annular space, absorbent material within the said annular space, and an internal wall within the said socket adapted for the retention of the said absorbent material therein, substantially as described. 15

HENRY COURTEEN.
